(57) **CLAIM**

The ornamental design for a light mounting bracket, as shown and described.

DESCRIPTION

FIG. 1 is a perspective view of a light mounting bracket showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view of a second embodiment of the light mounting bracket showing my new design;

FIG. 10 is a perspective view of the light mounting bracket, shown in a position of use;

FIG. 11 is a partial enlarged view of FIG. 1;

FIG. 12 is a partial enlarged view of FIG. 1;

FIG. 13 is a partial enlarged view of FIG. 2; and,

FIG. 14 is a partial enlarged view of FIG. 3.

The broken lines in the figures are for the purposes of illustrating portions of the light mounting bracket, which form no part of the claimed design.

1 Claim, 12 Drawing Sheets
